UNITED STATES PATENT OFFICE

JOHN DI GAUDIO, OF BROOKLYN, NEW YORK, ASSIGNOR TO MODERN LIGHTING FIXTURE CO., INC., A CORPORATION OF NEW YORK

DESIGN FOR A CHANDELIER

Application filed June 11, 1929. Serial No. 31,634. Term of patent 3½ years.

To all whom it may concern:

Be it known that I, JOHN DI GAUDIO, a citizen of the United States of America, and a resident of Brooklyn, county of Kings, and State of New York, have invented a new, original, and ornamental Design for a Chandelier, of which the following is a specification, reference being had to the accompanying drawing, forming a part hereof.

In the drawing:

The design is characterized by the provision of a central spindle A, a plurality of braces B, each of which has small bars or straps C. The chandelier has arms for the support of candles or drop lights.

I claim:

The ornamental design for a chandelier, substantially as shown and described.

JOHN DI GAUDIO.
